ANTENNA PATTERN SYNTHESIZER

Gus Stavis, Ossining, N. Y., assignor to General Precision Laboratory Incorporated, a corporation of New York

Application September 25, 1956, Serial No. 611,898

5 Claims. (Cl. 343—703)

This invention relates to apparatus for synthesizing and displaying the radiation pattern of a linear array antenna.

Linear array antennas composed of isotropic radiating elements emit energy in one or more cones the axes of which coincide with the axis of the array. At the present time the most widely used class of linear arrays is that class in which the spacing between elements is uniform and in which the phase of the energy emitted progresses uniformly from element to element. All linear array antennas of this class have a basic radiation pattern comprising a number of major lobes for which the radiation from all the elements combines in phase and a number of minor lobes of smaller amplitudes between the major lobes. Variation of the spacing between elements varies the number of lobes (both major and minor) while variation in the phase progression shifts the angle at which the lobes appear.

The radiation patterns of linear arrays having uniform spacing and phase progression are well known to those skilled in the art. However, the patterns for non-uniform arrays are less well known, partly because the possibilities are so numerous and partly because the calculations, although straightforward, are rather tedious. Apparatus which would synthesize and display the pattern of any linear array antenna would greatly simplify the study of non-uniform arrays whether the non-uniformities are intentionally included in the design or are introduced inadvertently because of manufacturing inaccuracies.

An object of this invention is to synthesize the radiation pattern of a linear array antenna.

Another object is to derive a voltage the time variations of which are analogous to the spatial variations of the power radiated by a linear array antenna.

Another object is to create a visual display which is analogous to the power radiated by a linear array antenna as a function of the angle of observation.

Briefly stated, the invention comprises several variable frequency pulsed oscillators, one for each element in the array to be synthesized. The relative starting times of the oscillators are individually adjustable. The output of each oscillator is split into an in-phase and a quadrature component. All of the in-phase components are added together and passed through a squaring circuit to derive a voltage proportional to the square of the sum. Similarly, all of the quadrature components are added together and then squared. The two squared voltages are then added together and the resulting voltage varies with time in a manner analogous to the way in which the power radiated by a linear array antenna varies with the angle of observation. The variations of the resulting voltage may be displayed on an oscilloscope.

For a clearer understanding of the invention reference may be made to the following detailed description and the accompanying drawing in which:

Figure 1 is a diagrammatic showing of the radiation of a linear array antenna;

2

Figure 2 is a block diagram of a preferred form of the invention; and

Figure 3 is a group of curves useful in explaining the invention.

Referring first to Fig. 1, there is shown diagrammatically a linear array antenna comprising a plurality of individual isotropic radiating elements 10, 11, 12, 13 etc. The distances of the elements 11, 12, 13 etc. from the first element 10 are denoted by s_1, s_2, s_3 etc. Consider 10 the field strength at any remote point P far enough from the array so that (1) the attenuation of the wave energy from each element is substantially the same and (2) lines drawn from each element to the point P are substantially parallel and make an angle θ with the normal 15 to the axis of the array. The total field strength will be the sum of the contributions from each element and, neglecting attenuation, may be expressed as

$$F(\theta) = I_0 \sin(\omega t + \phi_0) + I_1 \sin\left(\omega t + \phi_1 + \frac{2\pi s_1}{\lambda} \sin \theta\right) + \dots \quad (1)$$

where

25 $F(\theta)$ = total field strength
 I_0, I_1, I_2 etc. = current in the individual radiating elements
 ω = angular velocity of the excitation
 ϕ_0, ϕ_1, ϕ_2 etc. = in phase of the energy emitted by the individual elements
 30 s_1, s_2, s_3 etc. = distance of the elements from the first elements
 λ = free space wavelength
 θ = angle of observation

35 Equation 1 can be expressed as the summation of the typical terms and when so expressed becomes

$$F(\theta) = \sum_{n=0}^{n=n} I_n \sin\left(\omega t + \phi_n + \frac{2\pi s_n}{\lambda} \sin \theta\right) \quad (2)$$

40 Equation 2 can be transformed by employing the trigonometric expression for the sine of the sum of two angles.

$$45 F(\theta) = \sum_{n=0}^{n=n} I_n \left[\sin \omega t \cos\left(\phi_n + \frac{2\pi s_n}{\lambda} \sin \theta\right) + \cos \omega t \sin\left(\phi_n + \frac{2\pi s_n}{\lambda} \sin \theta\right) \right] \quad (3)$$

$$50 F(\theta) = \sin \omega t \sum_{n=0}^{n=n} I_n \cos\left(\phi_n + \frac{2\pi s_n}{\lambda} \sin \theta\right) + \cos \omega t \sum_{n=0}^{n=n} I_n \sin\left(\phi_n + \frac{2\pi s_n}{\lambda} \sin \theta\right) \quad (4)$$

55 An expression for the absolute value of Equation 4 can be derived by the use of the trigonometric identity

$$60 A \sin \omega t + B \cos \omega t = \sqrt{A^2 + B^2} \sin\left(\omega t + \arctan \frac{B}{A}\right) \quad (5)$$

Transformation of Equation 4 by the above identity gives an expression for the square of the absolute value of the field strength as follows.

$$65 |F(\theta)|^2 = \left\{ \sum_{n=0}^{n=n} \left[I_n \cos\left(\phi_n + \frac{2\pi s_n}{\lambda} \sin \theta\right) \right] \right\}^2 + \left\{ \sum_{n=0}^{n=n} \left[I_n \sin\left(\phi_n + \frac{2\pi s_n}{\lambda} \sin \theta\right) \right] \right\}^2 \quad (6)$$

Equation 6, which expresses the field strength as a function of θ , can be transformed to an analogue so as to express field strength as a function of time by means of two simple substitutions. First, let

$$\frac{2\pi s_n}{\lambda} \sin \theta = \rho_n t_n \quad (7)$$

Second, note that ϕ_n represents a fixed angle and can be thought of as the angle passed through in a fixed period of time t_n . The angular velocity may be selected arbitrarily provided that t_n is chosen accordingly. Therefore, let

$$\phi_n = \rho_n t_n \quad (8)$$

Making these substitutions, Equation 6 becomes

$$|F(t)|^2 = \left\{ \sum_{n=0}^{n=n} [I_n \cos (\rho_n t_n + \rho_n t)] \right\}^2 + \left\{ \sum_{n=0}^{n=n} [I_n \sin (\rho_n t_n + \rho_n t)] \right\}^2 \quad (9)$$

$$|F(t)|^2 = \left\{ \sum_{n=0}^{n=n} [I_n \cos \rho_n (t_n + t)] \right\}^2 + \left\{ \sum_{n=0}^{n=n} [I_n \sin \rho_n (t_n + t)] \right\}^2 \quad (10)$$

A voltage the magnitude of which varies with time in accordance with Equation 10 can be synthesized with the apparatus shown in Fig. 2.

Referring now to Fig. 2, there is shown a timing wave generator 21 which may be a free running multivibrator. The frequency is not critical but in one particular embodiment is selected to be 1667 C. P. S. The generator 21 triggers a saw-tooth wave form generator 22 which, of course, will also have a frequency of 1667 C. P. S. The saw-tooth generator should have a linear rise in voltage for a period of approximately 120 microseconds but the recovery time is not critical since the rising portion of the wave form is the only portion utilized and is of much shorter duration than the period of the wave itself. This generator may, for example, be a phantastron circuit. The output of the generator 22 appears on conductor 23 so that it may be led to several circuits each comprising a chain of components. The first chain comprises a trigger generator 24 the purpose of which is to generate a short positive pulse at a pre-selected time in each cycle. The generator 24 may, for example, comprise a blocking oscillator operation of which is inhibited until a control voltage has reached a predetermined magnitude. The control voltage in this case is the rising saw-tooth wave form of generator 22 and the circuit is arranged to initially operate the oscillator at any preselected interval of the rise time of the saw-tooth wave form. The output pulse of the generator 24 is utilized to trigger a gate generator 25 which may comprise a multivibrator having a frequency of approximately 1000 C. P. S. so that a negative gate is generated for a duration of approximately 500 microseconds. This negative gate is led to a pulsed oscillator 26 so that oscillations are generated only during the period of the negative gate. The oscillator 26 should be adjustable in frequency and it may, for example, have a range of from 10 kc. p. s. to 40 kc. p. s. The output of the oscillator 26 is controlled in magnitude by potentiometer 27 the slider of which is connected to two additional potentiometers 28 and 29 so that there are available two outputs the amplitudes of which may be adjusted simultaneously by the potentiometer 27 and individually by the potentiometers 28 and 29. The slider of the potentiometer 28 is connected to a conductor 31 which, as will be more fully explained, has a potential thereon which may be represented by the expression $I_1 \sin \rho_1 (t_1 + t)$. The slider of potentiometer 29 is connected to a phase shift-

ing circuit 32 the purpose of which is to provide an output in quadrature with the voltage on conductor 31. The phase shifter 32 may comprise an amplifier and a Miller integrator, and the output on conductor 33 may be represented by the expression $I_1 \cos \rho_1 (t_1 + t)$.

Additional chains of components similar to that just described are also connected to conductor 23. One of these is shown and comprises a trigger generator 36, a gate generator 37, a pulsed oscillator 38, potentiometers 41, 42 and 43, and a phase shifter 44. Additional chains of components are represented by the dashed lines such as 45 and 46.

The output of all of the potentiometers such as 28 and 42, representing as they do sine functions, are led to an adding circuit 51 which derives an output proportional to the sum of the input voltages. The adding circuit may comprise a conventional parallel resistive adding network. Similarly, the outputs of the phase shifters such as 32 and 44, representing cosine functions, are led to an adding circuit 52 which may be identical to circuit 51 and which derives an output proportional to the sum of all of the inputs. The outputs of adding circuits of 51 and 52 are led to squaring circuits 53 and 54 respectively the purpose of each of which is to derive an output voltage the magnitude of which is proportional to the square of the input voltage. Each of the circuits 53 and 54 is preferably an electronic circuit comprising push-pull electronic tubes. The outputs of the two squaring circuits 53 and 54 are next added together by means of an adding circuit 55 which may also comprise a parallel resistor adding network. The sum voltage from the adding circuit 55 is led to the vertical deflection system of an oscilloscope 56, the horizontal sweep circuit of which is synchronized by the timing wave generator 21.

The output of the adding circuit 55 is a voltage the magnitude of which is proportional to the square of the field strength of the radiation pattern of the simulated linear array as can be seen by referring back to Equation 10. The oscillator 26 generates a voltage of the form $I_1 \sin \rho_1 t$. The initial phase of the oscillation is controlled by the starting time of the negative gate generated by the gate generator 25 which thereby alters the output so as to be of the form $I_1 \sin \rho_1 (t_1 + t)$. The magnitude of this voltage which is analogous to I_1 may be adjusted by means of the potentiometer 27. The remaining chains of components generate similar voltages corresponding to $I_2 \sin \rho_2 (t_2 + t)$, $I_3 \sin \rho_3 (t_3 + t)$, etc. The phase shifters 32, 44, etc. derive voltages which correspond to the terms $I_1 \cos \rho_1 (t_1 + t)$, $I_2 \cos \rho_2 (t_2 + t)$, $I_3 \cos \rho_3 (t_3 + t)$, etc. All of the sine functions are collected and added by the adding circuit 51 and are squared by the circuit 53. Similarly, all of cosine functions are collected and added by the adding circuit 52 and squared in the circuit 54. The squares are then added together in the circuit 55. The resulting voltage then is seen to correspond in form to the function of Equation 10.

Figure 3 shows the time relationship of the various wave forms mentioned in connection with Fig. 2. The specific frequencies and time durations shown in Fig. 3 are, of course, merely illustrative but the use of specific figures is an aid to understanding the invention. Reference character 61 denotes the wave form of the output of the timing wave generator 21 having a frequency of 1667 C. P. S. and a period of 600 μ sec. The positive going portion triggers the saw-tooth generator 22 which generates a linear rising voltage wave form 62 having a duration of approximately 120 μ sec. An early portion of the wave form 62, for example 10 μ sec. from the start, is selected as a reference time t_0 from which the remaining time intervals t_1 , t_2 , t_3 etc. are measured. As previously mentioned, the trigger generator 24 emits a pulse when the impressed voltage (wave 62) has reached a predetermined level. Thus a simple voltage

divider such as a potentiometer allows the time interval t_1 to be set at any value within the range of the wave form 62.

The pulse 63 from generator 24 triggers the gate generator 25 thereby initiating a negative going gate 64 of approximately 500 μ sec. duration. During this gate and only during this gate the oscillator 26 operates. The trigger generator 36 is adjusted to generate a pulse 65 at the time t_2 and this pulse initiates the negative gate 66 during which the oscillator 38 operates. In a similar fashion the remaining trigger generators are adjusted to generate pulses at the appropriate times.

The adjustment of the frequencies of the oscillators and the time intervals t_1 , t_2 etc. can best be understood by considering an example. Suppose it is required to simulate a six element linear array having the following spacings, phases, and relative illuminations:

Table I

Element	1	2	3	4	5	6
Spacing	0	.5 λ	.7 λ	1.4 λ	2.0 λ	3.0 λ
Phase (degrees)	+30	-60	-180	+90	-90	-235
Illumination	1	1.5	2.0	2.0	1.5	1.0

First consider the spacing. It will be recalled from Equation 7 that

$$\rho_n t = \frac{2\pi s_n}{\lambda} \sin \theta$$

and this relationship can be expressed in the form of two equations, thus:

$$t = k \sin \theta \quad (11)$$

$$\rho_n = \frac{1}{k} \frac{2\pi s_n}{\lambda} \quad (12)$$

The angular velocities ρ_1 , ρ_2 etc. (and the frequencies) are therefore seen to be directly proportional to the spacing. The first element has zero spacing from itself and it would appear to be necessary to make the frequency of oscillator 26 zero. In order to avoid this situation a fictitious element, called the zero order or zeroth element, is assumed to be positioned before the first element at any arbitrarily selected distance. It is convenient to assume this distance to be 1.0λ . The spacings of the remaining elements from the zeroth element thus are 1.0λ , 1.5λ , 1.7λ , 2.4λ , 3.0λ and 4.0λ respectively. The frequency for one of the oscillators may now be chosen arbitrarily and if we choose the frequency of oscillator 26 to be 10 kc. p. s. we note that 10 kc. p. s. corresponds to a spacing of one wavelength and the frequencies of the remaining oscillators will be 15, 17, 24, 30 and 40 kilocycles respectively.

Consider now the phase of the energy emitted by the individual radiating elements and the selection of the corresponding time intervals t_1 , t_2 etc. It is convenient to regard the element having the greatest lead as the reference element and to regard the remaining elements on lagging that element in phase. Since in this case element 4 has the greatest lead this element will be regarded as the reference element having zero phase and the phase of the elements 1-6 with respect to element 4 then become -60° , -150° , -270° , 0° , -180° and -325° respectively. It will be recalled from Equation 8 that

$$t_n = \frac{\phi_n}{\rho_n}$$

or

$$t_n = \frac{\phi_n T_n}{2\pi}$$

where T_n is the period of the n th oscillator in seconds, t_n is the time delay in seconds, and ϕ_n is the phase angle in radians. For the oscillator 26 the frequency of which

is 10 kc. p. s., the period is 100μ sec. and the time interval

$$t_1 = \frac{60}{360} \times 100 = 16.7 \mu \text{ sec.}$$

5 The time interval

$$t_2 = \frac{150}{360} \times 66.7 = 27.8 \mu \text{ sec.}$$

- 10 The remaining intervals t_3 to t_6 are similarly computed and are found to be 43.4, 0, 16.7 and 22.6 microseconds respectively. Table II below summarizes the above computations.

Table II

Element	0	1	2	3	4	5	6
Spacing from No. 1	0	0	.5 λ	.7 λ	1.4 λ	2.0 λ	3.0 λ
Spacing from No. 0	0	1.0	1.5 λ	1.7 λ	2.4 λ	3.0 λ	4.0 λ
Frequency (kc.)	0	10	15	17	24	30	40
Period (μ sec.)	100	66.7	58.8	41.7	33.3	25	20
Phase (degrees)	+30	-60	-180	-180	-90	-90	-235
Adjusted Phase	-60	-150	-270	0	-180	-180	-325
Time (μ sec.)	16.7	27.8	43.4	0	16.7	22.6	30
Illumination	1.0	1.5	2.0	2.0	1.5	1.0	1.0

- 25 To set up the apparatus to display the pattern of the above discussed array, computations such as shown in Table II are first made. Next the apparatus is turned on and the amplitude and duration of the linear portion of the sawtooth wave are measured. Thus a linear relation between voltage and time is established.

- 30 Next the fourth trigger generator is adjusted so that a pulse is generated when the voltage of the sawtooth wave has risen to the point marked t_0 in Fig. 3. If the trigger generator is a blocking oscillator this adjustment may be made by setting the reference voltage level with an internal potentiometer. Next the reference voltage levels of the remaining trigger generators are adjusted so that pulses are generated at the proper times as shown in Table II.

- 40 The frequency of the oscillator 26 should next be adjusted to the value shown by Table II, that is, 10 kc. p. s. This adjustment can be made by comparing the output of oscillator 26 with the output of an adjustable standard reference oscillator, preferably using

- 45 an oscilloscope to make the comparison. After the frequency has been set, the voltages of conductors 31 and 33 should be made equal by adjusting the potentiometers 28 and 29. The remaining oscillators are adjusted in the same manner.

- 50 The illumination may be adjusted to the relative values indicated in Table II by means of the potentiometers 27, 41, and like potentiometers in each of the remaining circuits.

- 55 The sweep circuit of the oscilloscope 56 should be adjusted to have a rise time of just under 600 microseconds, as shown by the curve 67 of Fig. 3, so that it can be synchronized by the positive going portion of the wave form 61 from the timing pulse generator 21. On the oscilloscope screen the abscissa is, of course,

- 60 time but is directly proportional to $\sin \theta$ and the factor of proportionality can be found from Equations 11 and 12. In the example being considered a spacing of 1.0λ corresponds to a frequency of 10 kc. p. s. From Equation 12 k is found to be equal to 100 microseconds.

- 65 Equation 11 shows that 100 microseconds corresponds to ninety degrees of variation of θ , so that 400 microseconds corresponds to 360° variation of θ .

- From the foregoing description it is seen that the present invention provides apparatus by means of which 70 the radiation pattern of virtually any linear array antenna may be synthesized and visually displayed. The spacing between radiators, the phase of the energy emitted by each radiator, and the relative magnitude of the illumination may be individually adjusted and need not vary uniformly from radiator to radiator.

What is claimed is:

1. An antenna pattern synthesizer comprising, a plurality of variable frequency oscillators, means for repeatedly starting and stopping the generation of oscillations, means for deriving from the output of each of said oscillators first and second voltage components in quadrature with each other, means for adding all of said first components together to obtain a first summation voltage, means for adding all of said second components together to obtain a second summation voltage, means for deriving a first squared voltage proportional to the square of said first summation voltage, means for deriving a second squared voltage proportional to the square of said second summation voltage, and means for adding said first and second squared voltages to obtain a resulting voltage the amplitude variations of which as a function of time are analogous to the variations in the power radiated by an antenna as a function of the angle of observation.

2. An antenna pattern synthesizer comprising, a plurality of variable frequency oscillators, a timing wave generator, means controlled by said timing wave generator for repeatedly starting and stopping the operation of said oscillators, means for deriving from the output of each of said oscillators first and second voltage components in quadrature with each other, means for adding all of said first components together to obtain a first summation voltage, means for adding all of said second components together to obtain a second summation voltage, means for deriving a first squared voltage proportional to the square of said first summation voltage, means for deriving a second squared voltage proportional to the square of said second summation voltage, means for adding said first and second squared voltages to obtain a resulting voltage, and means controlled by said timing wave generator for visually displaying the amplitude of said resulting voltage as a function of time.

3. An antenna pattern synthesizer comprising, a plurality of variable frequency oscillators, a timing wave generator, means controlled by said timing wave generator for repeatedly starting and stopping the operation of said oscillators, said means including means for adjusting the relative times at which the generation of oscillations is started in each of said oscillators, means for adding together the voltage outputs of all of said oscillators to obtain a first voltage, means for deriving a second voltage proportional to the square of said first voltage, means for deriving a plurality of voltages each in quadrature with the voltage output of one of said oscillators, means for adding together all of said quadrature voltages to obtain a third voltage, means for deriving a fourth voltage proportional to the square of said third voltage, means for adding together said second and fourth voltages to obtain a fifth voltage, an oscilloscope, means for applying said fifth voltage to the vertical deflection system of said oscilloscope, and means for controlling the

horizontal deflection system of said oscilloscope by said timing wave generator.

4. An antenna pattern synthesizer comprising, a plurality of variable frequency oscillators, a timing wave generator, means controlled by said timing wave generator for repeatedly starting and stopping the operation of all of said oscillators, said means including means for varying the relative times at which the generation of oscillations is initiated by each of said oscillators, means for individually varying the magnitude of the output of said oscillators, means for deriving from the output of each of said oscillators first and second voltage components in quadrature with each other, means for adding all of said first components together to obtain a first summation voltage, means for adding all of said second components together to obtain a second summation voltage, means for deriving a first squared voltage proportional to the square of said first summation voltage, means for deriving a second squared voltage proportional to the square of said second summation voltage, means for adding said first and second squared voltages to obtain a resulting voltage, and means controlled by said timing wave generator for visually displaying the amplitude of said resulting voltage as a function of time.

5. An antenna pattern synthesizer comprising, a plurality of variable frequency oscillators, a timing wave generator, means controlled by said timing wave generator for repeatedly starting and stopping the operation of all of said oscillators, said means including means for varying the relative times at which the generation of oscillations is initiated by each of said oscillators, means for individually varying the magnitude of the output of said oscillators, means for deriving from the output of each of said oscillators first and second voltage components equal in magnitude and in phase quadrature with each other, means for adding all of said first components together to obtain a first summation voltage, means for adding all of said second components together to obtain a second summation voltage, means for deriving a first squared voltage proportional to the square of said first summation voltage, means for deriving a second squared voltage proportional to the square of said second summation voltage, means for adding said first and second squared voltages to obtain a resulting voltage, an oscilloscope, means for applying said resulting voltage to the vertical deflection system of said oscilloscope, and means for controlling the horizontal deflection system of said oscilloscope by said timing wave generator.
